TION OF NEW JERSEY.

LEATHER-EDGE-FINISHING MACHINE.

1,195,674.

Specification of Letters Patent.

Patented Aug. 22, 1916.

Application filed January 12, 1912. Serial No. 670,801.

To all whom it may concern:

Be it known that we, EDWARD S. HALSEY and GEORGE G. PERKINS, of Lynn, in the county of Essex and State of Massachusetts, 5 have invented certain new and useful Improvements in Leather-Edge-Finishing Machines, of which the following is a specification.

The present invention relates to a machine for carrying out the process disclosed in our prior Patent No. 1,047,211 and is herein illustrated in connection with a machine for applying intense and concentrated shriveling heat to the flesh side of a piece of leather 15 along a narrow line at the margin and to the raw edge itself, this application being accomplished by a hot tool trailing said edge and margin so as to shrink the margin on the flesh side and curl back the grain or 20 finished side of the leather toward the shrunken side whereby there is presented a partially rounded finished edge in place of the original raw cut edge.

Our object is primarily to save the time, 25 labor, and expense of skiving, cementing, folding back and pressing the edges, particularly as is required in high grade shoemaking, and to produce at least an equally desirable result as with the more laborious 30 method referred to, also to save the cement and leather wasted in folding.

Referring to the drawings which illustrate our invention, similar numerals and letters refer to similar parts throughout the 35 several views, in which—

Figure 1 is a plan view of a complete machine suitable for accomplishing the results described, while Fig. 2 is a vertical section on line 2—2 of Fig. 1. Figs. 3 and 4 are 40 front and side elevations of an electrically heated scorching tool as used in Figs. 1 and 2. Fig. 5 shows a front elevation of a gas heated tool which may be used alternatively with the tool shown in Figs. 1 and 2. Fig. 45 6 shows a cross section through a fragment of leather to illustrate the finished edge characteristic of our method. Fig. 7 is a cross-section through the roller shaft 9 and

its sliding bearing 23, looking from the front of the machine.

The same reference characters indicate the same parts in all the figures.

In the embodiment of the machine which is illustrated herein, there is a base consisting of top and bottom plates *a* and *b* and posts *c*, the top plate constituting a table or support on which the leather to be acted on may be placed. To the side of the base is secured a bracket 20 which provides a bearing for and supports a driving shaft 9, 60 carrying a pulley 22 which is keyed to the shaft. This pulley is the primary driving element and is rotated by a belt 221.

An upright shaft 161 is supported at its lower end in a step bearing 162 in the bottom plate *b* of the machine frame, and the upper end of the shaft is contained in the bearing of the top plate *a*. The step bearing 162 is adjustable longitudinally of the shaft, being conveniently a screw plug threaded 65 into the plate *b*, so that it may be employed to adjust the shaft and bring the end face 16 thereof approximately into the plane of the upper surface of the plate or work support *a*. The upper end of shaft 161 is recessed and contains a member 28 which is 70 structurally a tubular stud or roll, and is functionally a pressing member or edge presser for acting upon the edge of the leather to be treated, in a manner presently 75 to be described. Said stud or roll 28 is movable longitudinally upon a rod or post 281, which in this machine is a screw passing through the roll 28 into the shaft. A spring 80 282 in the recess beneath the roll holds the latter elevated to the full extent permitted by the head of the screw post 281. On the upper end of the stud or roll 28 there is an outwardly projecting flange 17. The shaft is rotated by a pulley 18 secured thereon, to 85 which motion is given by a belt 181 driven by a pulley 222 connected with the pulley 22, and passing around guide pulleys 19 mounted on the bracket 20.

The machine includes a means for applying intense heat to the surface of a leather

piece over a limited area of such surface. One such means, which at the present time we consider preferable to others, is illustrated in Figs. 1, 2, 3, and 4. This means is 5 an electrically heated searing or scorching tool consisting of an electrical conductor 1 having a sufficiently high resistance, and being preferably a wire bent double at approximately its middle point and having 10 its ends somewhat separated and bent up at right angles to its looped or doubled portion on a gradual curve, as indicated in Fig. 4. The ends of this heating or searing element are secured in mechanical and electrical connection with conducting bars or rods 2, which for mechanical convenience are semi-cylindrical and are placed with their flat sides adjacent to one another in a holding sleeve or shell 3. Insulation is 15 placed between the two bars 2 and also between the latter and the outer shell 3, as shown by the heavy lines in Figs. 1 and 3. While the shape and construction of the heating tool may be varied without departing from the broader aspects of the invention, yet the particular construction here illustrated and described is particularly important because it enables a compact and efficient tool to be produced at low cost. 20 When the conducting bars 2 are connected in an electrical circuit, and a current is allowed to flow, the heating element 1 is heated to a high temperature which depends on its electrical resistance and the intensity 25 of the current.

Without intending to limit ourselves to any particular material to be used for the heating element or to any particular degree of heat to which the same is to be raised 30 while in use, we may say that we prefer to make the heating element of platinum or of an alloy having a high resistance, and to bring the element to a bright red or white heat when in use.

45 The tool last above described is secured in a holder 4 so shaped as partially to embrace the body portion or shank of the tool, by means of a set screw 5 which is supported by a bracket 41 carried by the holder 4, the 50 set screw being located opposite to the open side of the holder and extending toward the latter.

The holder is supported by a plate 12 mounted on posts 15 rising from the top 55 plate or table *a*, being thus supported by flat springs 6, 6 having slots through which a holding screw 14 passes into the plate 12. A spacing sleeve or thimble 7 is mounted on the screw 14 between the springs 6, 6, holding 60 the springs apart and serving to clamp them both when the screw 14 is turned. The slots in the spring strips 6, 6 allow the holder 4 and the tool carried thereby to be adjusted both angularly about the screw 14 and to-

ward or away from the same, whereby its 65 position may be accurately located with respect to the shaft 161, stud 28, a post or pin 24 rising from the table *a*, and a feed wheel 8.

Feed wheel 8 is mounted on the shaft 9 70 and is arranged over the table *a* in contact with the flange 17 of the stud 28. Shaft 9 passes through a sliding adjustable bearing 23 having guides through which the posts 15 pass, on which the bearing may move toward and away from the table. A spring 11 secured to the plate 12 presses downwardly 75 on the bearing 23, urging the feed wheel toward the table. A screw threaded through the plate 12 regulates the pressure of spring 11. A spring 21 secured to the bracket 20 bears on the hub portion of the pulley 22 and through the latter exerts end thrust on the shaft 9 tending to keep the feed wheel 8 in contact with the flange 17. A screw 211 80 regulates the pressure of spring 21.

The end surface 16 of the shaft 161 forms a part of the work support, the major part of which is constituted by the table *a*, and supports the edge portion of the leather 90 piece near the part acted upon by the heating tool. For this reason we call the supporting surface 16 a turntable. The feed wheel 8 is located with a part of its feeding surface overlapping this turntable, whereby 95 it is adapted to coöperate therewith in gripping the upper side of the edge portion of a sheet of leather which is laid on the table *a* and turntable 16 with its edge in contact with the side of stud 28. The arrangement 100 of transmission belt 181 is such as to cause the adjacent parts of the turntable 16 and feed wheel 8 to move in the same direction, whereby the edge of a piece gripped between the turntable and feed wheel is fed. The 105 turntable and feed wheel thus constitute complementary work gripping and feeding members or means. The spring 11 causes the feed wheel to exert a resilient pressure against the piece and allows it to yield for 110 inequalities in thickness of the piece.

The heating tool is located at one side of and close to the point where the feed wheel and turntable grip the leather. The point at which the wire constituting the heating 115 element 1 is bent double and forms the end of that element, and the portion between such end and the bend, previously described, lies approximately parallel to the surface of the work support and is adapted to bear on the surface of a leather piece placed on the support and properly positioned. The form of the heating element gives an area of contact with the leather having very slight width and greater length, in order to apply 120 heat to each point of the leather fed past it for a sufficiently long time to secure the results desired. The longitudinal dimension 125

of this part of the tool is not in or parallel to the plane of rotation of the feed wheel but is inclined to such plane, as shown in Fig. 1.

6 The stud 24 previously mentioned rises from the table α at a point near the end of the operative portion of the heating element which is more remote from the feed wheel. This stud, one function of which is to serve 10 as an edge gage or guide, has a flaring base which directs or bends the edge of the leather upwardly and holds it against the searing tool.

The operation of the machine can now be 13 understood. The leather piece to be treated is laid on the table α with that edge which is to be finished in contact with the stud 24 and the stud 28, and ready to be passed under the feed wheel 8 in the direction of the 20 arrow shown in Fig. 1. Current being allowed to pass through the tool, the heating element 1 is brought to the temperature desired and is caused to apply heat to the surface of the leather immediately beneath it. Ordinarily it rests upon the surface of the leather, being yieldingly held against the leather by the springs 6, 6 and adapted to yield for irregularities in the thickness of the leather and to permit parts of greater 25 thickness to pass without binding. The distance away from the edge at which the element 1 acts on the leather is regulated by the adjustment of the tool with respect to the studs 24 and 28. Ordinarily the heating 30 tool is arranged to act on a narrow path on the flesh side of the leather piece adjoining the edge of the piece. As the leather is fed under the heating tool it is progressively acted upon by the tool throughout the extent of the edge to be treated. The leather 35 is laid with its grain side toward the table and its flesh side exposed to the heating tool. The action of the heating tool is to sear, momentarily render plastic, and con- 40 agulate the flesh side of the leather at or near the edge, thus shrinking and drawing back the leather on that side, and curling over the grain surface at the edge. Upon 45 cooling, the flesh side is left in a permanently shrunken and hardened state, the piece having a smooth rounded edge over which the grain surface of the leather extends as far as the flesh side, giving the edge 50 the same appearance as when skived and folded.

We have found that although the shriveling of the flesh side in the manner described produces the desired effect of curling back the edge, yet we have been able to secure a 55 more uniform and complete backward curling by mechanically molding the leather when it is still plastic, by crowding it against molding surfaces. It is for this purpose as well for the purpose of cooling

the leather, that we provide the rolling stud 28 and the fixed stud 24, and it is also the reason for arranging the searing tool and the line of feed oblique to the plane of rotation of the feeding wheel 8. This obliquity of the line of feed to the feeding wheel 70 causes the latter to crowd the edge of the leather against the stud 28, immediately after the heated portion of the leather leaves the heating tool; and while, therefore, it is still hot and plastic. The edge thus 75 confined in the space between the flange 17, the turntable 16, and the side of the stud 28, and being pressed into such space by the feed wheel, is molded, and given a form which is approximately uniform at all 80 points along the edge. At the same time the molding members, which are comparatively cool, chill the leather and thereby set it in its molded shape.

Fig. 6 shows in cross section the final 85 shape of the finished edge. The grain side of the leather piece is indicated at G and the flesh side at F. It will be noted that the finished edge is rounded and that the grain surface extends on a smooth curve over this 90 finished edge to the flesh side.

We do not limit the invention to the use of an electrically heated scorching tool, as we contemplate the use of other forms of heating means. One such form is shown in 95 Fig. 5 where a gas heated tool is illustrated. This tool is preferably constructed of a hollow platinum point to which gas is conducted by a pipe 30. Within the hollow point is a platinum gauze portion operating 100 on a catalytic principle as commonly understood. In the side of the tool is a vent aperture 32 for escape of heating flame. This is merely one manner or form of heating tool which we may employ. A solid body heated 105 to the required point in any other way would be within the scope of the broader aspects of our invention, and so also would a jet of steam or flame or other highly heated gas, properly directed to act at the 110 desired point on the leather.

We have found that any destructive temperature, that is a temperature high enough to cause decomposition or destructive distillation of the leather, will answer in carrying out our invention, and that temperatures scarcely as high as red heat may be made to serve to some degree on some kinds of leather. In order to secure the best commercial results and efficient speeds of operation, however, we prefer to use scorching tools heated to a bright red or a white heat. The temperature of the tool and the speed of feeding must be adjusted according to the kind and tannage of the leather, and the skill of the operator in manipulating and feeding it. In any event the temperature and rate of feeding are so regulated that the leather 120

passes from the action of the scorching tool before the heat has penetrated sufficiently far into and through the leather to injure the appearance of its outer surface, or its strength.

The base of the stud 24 is made somewhat tapered or inclined as shown in Fig. 5 in order to turn up the edge at the point engaged by the scorching tool to facilitate the curling back of the edge, and for the same purpose the surface of the turntable 16 near the stud 28 is inclined outwardly as shown in Fig. 2.

It is to be understood that our process not only accomplishes the desired effect of curling back and rounding the edge of the leather in a permanent manner, but that at the same time it makes the more or less ragged back of the cut edge smooth and uniform and darkens it in color, owing to carbonization of the leather. The operation also tends to bring the edge of the piece to an even and uniform thickness.

We do not limit our invention to a machine having all the elements hereinbefore described, or to one in which the searing tool is relatively stationary and the leather is fed past the tool. Any machine including a heating means adapted to act on a limited area on the surface of a leather piece and to raise the temperature of the piece locally to such a temperature as to sear and shrink the part acted upon, and is arranged so that a relative motion between the piece and the tool may take place, is within the scope of our invention.

What we claim and desire to secure by Letters Patent is:

1. A machine for finishing the edge of a leather piece comprising a support for the piece, a searing tool held from movement in the line of feed, means for heating said tool to a temperature sufficiently high to sear or scorch the leather, and means for so guiding the piece that the tool is caused to act on the surface of the piece close to its edge.

2. A machine for finishing the edge of a leather piece, comprising a support for the piece, a tool held from movement in the line of feed arranged relatively to said support in a position to make contact with the surface of a leather piece placed between the support and the tool, and means for maintaining said tool at a temperature sufficiently high to sear the leather.

3. A machine for finishing the edge of a leather piece comprising a support for the piece, a searing tool held from movement in the line of feed, means for heating said tool to a temperature sufficiently high to sear or scorch the leather located adjacent to said support, and guiding means for the edge of the piece arranged so to locate the piece that a portion thereof close to its edge is exposed to the action of the tool.

4. A machine of the character described, comprising a searing tool, means for heating said tool to a temperature approximating incandescence, and means for holding a leather piece with a portion of the surface adjacent to an edge of the piece in contact with the tool.

5. A machine of the character described, comprising a searing tool, means for heating said tool to a temperature approximating that of incandescence, means for holding a leather piece with a portion of the surface adjacent to an edge of the piece in contact with the tool and means for feeding such piece past the tool.

6. A machine of the character described comprising a searing tool held from movement in the line of feed, means for heating said tool to a temperature at which it will scorch leather, means for holding a leather piece with a portion of the surface adjacent to an edge of the piece in contact with the tool, and means for exerting pressure against the edge of the piece.

7. A leather edge-finishing machine, comprising means for applying heat sufficient to sear or scorch leather to a limited area of the surface of a leather piece adjacent to and at the edge thereof, and means for exerting pressure against the edge of the piece adjacent to the heated area.

8. A leather edge-finishing machine, comprising means for applying heat sufficient to sear or scorch leather to a limited area of the surface of a leather piece adjacent to the edge thereof, means for exerting pressure against the edge of the piece adjacent to the heated area and means for feeding the piece past said heat applying and pressure exerting means to effect a progressive subjection of the edge portion of the piece to said means.

9. An apparatus for leather edge finishing comprising in combination, means for supporting a leather piece, a searing tool held from movement in the line of feed arranged relatively to said supporting means so as to engage the surface of a leather piece on said supporting means, means for heating the tool to a temperature sufficiently high to scorch leather, and an edge pressing member located in such relation to said supporting means as to engage the edge of a leather piece supported by said means, and in close proximity to said tool.

10. An apparatus for leather edge finishing, comprising, in combination, a tool adapted to bear upon a surface of a leather piece adjacent one edge thereof, means for heating said tool to a temperature such that it will scorch the leather, means for supporting said piece, a pressing member located adjacent the tool and arranged to engage the edge and upper marginal surface of said piece, and feeding means for carrying the

- piece past said tool constructed and arranged to crowd the piece against said pressing means.
11. A leather edge-finishing apparatus comprising guiding means adapted to be engaged by the edge of a leather piece, and heat applying means having a temperature higher than that at which decomposition of leather by heat commences, located in close proximity to said guiding means, whereby to apply scorching heat to a line on the surface and near the edge of a leather piece carried past said heating means with its edge in contact with said guiding means.
12. A leather edge-finishing apparatus comprising means for supporting and guiding the edge portion of a leather piece, and heat-applying means having a temperature higher than the temperature at which decomposition of leather by heat commences, so arranged with respect to said supporting and guiding means as to apply scorching heat to a limited area of the surface near the edge of a piece engaged with said supporting and guiding means.
13. A leather edge-finishing machine comprising in combination a heating tool maintained during operation at a temperature sufficiently high to scorch leather, and being constructed with an elongated narrow contacting portion, and means for carrying a leather piece past and substantially in contact with said tool, at a rate such that the surface of the piece adjacent to the tool is destructively affected by the heat of the tool, while the opposite face of the piece is unaffected.
14. A leather edge-finishing machine comprising in combination a heating tool maintained during operation at a temperature sufficiently high to scorch leather, and being constructed with an elongated narrow contacting portion, and means for causing a narrow portion extending along and adjacent to the edge of a leather piece, on one surface of the piece to be exposed temporarily and progressively to the action of said tool for a time sufficiently long to cause contraction of the surface next to the tool, and insufficiently long to burn or otherwise injure the opposite face of the piece.
15. An apparatus of the character described comprising co-operating feed members adapted to grip the edge of a leather piece, one of said members having its axis approximately perpendicular to the plane of the piece, an edge presser mounted upon said last named member, and a heated scorching tool having an elongated operative element beside and extending toward said feed members, the complementary feed member having an axis approximately parallel to the plane of the work and inclined to the direction in which said tool extends, whereby the plane of rotation of said member is oblique to the line in which the work is fed past the tool, and the edge of the work is thereby crowded against the edge of the edge presser.
16. A machine of the character described comprising complementary work feeding members adapted to engage opposite faces of a leather piece adjacent to an edge thereof, an edge presser mounted to cross the edge of a piece engaged with said members, and a heated scorching tool adapted to engage one surface of the piece near its edge, whereby to scorch and contract such surface and curl over the adjacent edge, said tool being so located that a line therefrom to the point at which said members engage the work is oblique to the direction of movement of one of the feed members which engages the work, whereby said feed member is caused to force the edge of the work against the edge presser.
17. A leather edge-finishing machine comprising a work support, a post rising above said work support, a searing tool yieldingly held by said post at a distance above the work support approximately equal to the thickness of a thin sheet of leather, an edge guide rising from the work support adjacent to the searing tool, and a rotating feed roller above the work support and near said edge guide, arranged to rotate in a plane making an oblique angle with a line from the searing tool to the active point of the roll.
18. A machine of the character described comprising a rotating member or turntable having a face adapted to support the edge of a leather piece, a feed roll arranged over said turntable and yieldingly pressed toward the same for engaging a piece laid on said turntable, a stud rising above said turntable arranged to cross and be engaged by the edge of a piece held by said turntable and feed roll, and having a flange overhanging the adjacent part of the table, and a heated searing tool adjacent to said feed roll in position to heat the surface, adjacent to the edge, of a piece engaged by said roll.
19. A machine of the character described comprising a rotating member or turntable having a face adapted to support the edge of a leather piece, a feed roll arranged over said turntable and yieldingly pressed toward the same for engaging a piece laid on said turntable, a stud rising above said turntable arranged to cross and be engaged by the edge of a piece held by said turntable and feed roll, and having a flange overhanging the adjacent part of the table, and a heated searing tool adjacent to said feed roll in position to heat the surface, adjacent to the edge, of a piece engaged by said tool and means for yieldingly supporting said tool, to permit displacement there-

of for irregularities in the thickness of the piece.

20. A machine for finishing the edge of a piece of leather comprising a support for the piece, and means for shrinking the margin on one side of said piece in such manner that the margin of the unshrunken side is caused to curl toward the shrunken side to present a finished edge. 70

10 21. A machine for finishing the edge of a piece of leather, comprising a support for the piece, and means for progressively shrinking the margin on one side of said piece in such manner that the margin of the unshrunken side is caused to curl toward the shrunken side to present a finished edge. 75

15 22. A machine for finishing the edge of a piece of leather, comprising a support for the piece, and means for heating the surface of the piece adjacent to one edge thereof to a temperature sufficient to shrink such surface. 80

20 23. A machine for finishing the edge of a piece of leather comprising means for holding a piece of leather, means for heating one surface of such a piece at the margin thereof to a temperature sufficiently high to shrink such surface, and means for limiting the time during which the piece is subjected to said heating means to a period insufficient to permit penetration of the shrinking temperature to the opposite surface of the piece, whereby the margin of the unshrunken surface is caused to curl toward the shrunken surface to produce a finished edge. 90

25 24. A machine for finishing the edge of a piece of leather comprising means for holding a piece of leather, means for heating one surface of such a piece at the margin thereof to a temperature sufficiently high to shrink such surface, and means for removing the part of such piece which is subjected to the action of said heating means from the influence of such action before the shrinking temperature has penetrated to the opposite surface of such part, whereby the unshrunken side of the piece is curled toward the shrunken side. 100

30 25. A machine for finishing the edge of a piece of leather, comprising a support for the piece, means for heating the surface of the piece adjacent to one edge thereof to a temperature sufficient to shrink such surface, and means for feeding the piece at a rate of speed sufficiently rapid to remove the piece from the influence of said heating means before the shrinking temperature has penetrated to the opposite side of the piece. 105

35 26. A machine for leather edge finishing comprising a support, a guide arranged to engage the edge of a leather piece on said support, a tool arranged over said support in position to make contact with a surface of

the piece at and adjacent to such edge, means for heating said tool to the temperature at which it will shrink leather, and means for feeding the piece past said tool and guide at such a rate as to remove the portion thereof on which said tool acts from the influence of said tool before the shrinking temperature can penetrate to the opposite surface of the piece

75 27. A machine for finishing the edge of a piece of leather comprising a support for the piece, a searing tool, means for heating said tool to a temperature sufficiently high to sear the leather, and means for causing said tool to traverse the margin of said piece in such manner that the traversed side of the margin is shrunk and the untraversed side caused to curl toward the traversed side.

80 28. A machine for finishing the edge of a piece of leather comprising a support for said piece, a searing tool, and means for feeding said piece past said tool with said tool in contact with the margin and extreme edge of said piece in such manner that the seared margin is shrunk on one side, and the margin on the other side is caused to curl toward the shrunken side to present a finished edge. 90

85 29. A machine for finishing the edge of a piece of leather, comprising means for rendering the piece temporarily plastic at the edge thereof, and means for molding said edge into finished form while the same is plastic. 95

90 30. A machine for finishing the edge of a leather piece, comprising means for applying to one side of the piece at the margin thereof heat sufficiently intense to render the leather temporarily plastic, and edge-forming means arranged to apply pressure against the edge of the piece while the margin is in the plastic condition. 100

105 31. A machine for finishing the edge of a leather piece, comprising heat-applying means having a temperature sufficiently high to render leather temporarily plastic, feeding means arranged and operated to feed the margin of said piece past said heat-applying means, with one surface of the piece in contact therewith, and molding means at one side of the feeding path of said margin and arranged to bear on the edge of the piece in such proximity to the heat-applying means as to apply pressure to the leather while the same remains plastic. 110

115 32. A machine for finishing the edge of a leather piece, comprising heat applying means and edge molding means in proximity, and feeding means arranged and operating to feed the edge portion of a leather piece progressively past the said heating means with the surface at such edge in contact therewith, and thence to said molding means, said heating means having 120

a temperature sufficiently high to render the leather temporarily plastic, and the molding means being in such proximity to the heating means as to act on the leather while the same remains in the plastic condition.

5 33. A leather edge finishing machine, comprising a support for a piece of leather and heat-applying means arranged over said support and adapted to apply heat of an intensity sufficient to shrink leather, said heat-applying means being arranged yieldingly to make heat-transferring contact on a piece on said support, with a pressure less than sufficient to crush the leather.

15 34. A leather edge finishing machine, comprising a support for a piece of leather and heat-applying means arranged over said support and adapted to apply heat of an intensity sufficient to soften leather, and means 20 for so holding said heat-applying means as to cause the same to make light yielding contact with a piece on said support with a pressure insufficient to cause crushing of the softened leather.

25 35. A machine for finishing the edge of a piece of leather comprising a support for said piece, a searing tool, means for causing said tool to sear the margin of said piece, and means for bending the edge of the piece 30 toward said tool.

36. A machine for finishing the edge of a piece of leather comprising a support for said piece, a searing tool, means for causing said tool to act upon the margin of said piece, and means for displacing the margin of said piece away from the plane of said support and toward said tool.

40 37. A machine for finishing the edge of a piece of leather comprising a support for said piece, a searing tool, means for causing said tool to act upon the margin of said piece, and an edge gage the base of which extends beneath the edge of said piece and directs said edge upwardly toward said tool.

45 38. A machine for finishing the edge of a piece of leather comprising a support for said piece, a searing tool, means for causing said tool to act progressively upon the margin of said piece and means for bending the edge of the piece toward said tool.

50 39. A machine for finishing the edge of a piece of leather comprising a support for said piece, a searing tool, an edge gage located adjacent said tool, said gage having an inclined portion adapted to bend the edge of said piece toward said tool, and means for causing relative movement between said piece and said tool and edge gage to shrink the margin of said piece on one side and thereby to cause the margin on the other side to curl toward the shrunken side.

55 40. A machine for finishing the edge of a piece of leather comprising a support for

said piece, a searing tool arranged to act on the margin on one side of said piece, and an edge molding member arranged to act upon the edge of said piece subsequently to the action of the searing tool.

41. A machine for finishing the edge of a piece of leather comprising a support, a searing tool arranged to act upon and soften the margin of a leather piece on said support, and an edge molding member arranged in relation to said tool to act upon and mold the edge of the piece subsequently to the action of said tool and while the piece remains in softened condition.

45 42. A machine for finishing the edge of a piece of leather comprising a searing tool having a temperature high enough to sear and soften leather, an edge molding device, and means for producing a relative movement between a leather piece and said tool 85 and molding device in such manner that the margin of the piece is first subjected to the action of said tool and then to said device; said device being located in such proximity to the searing tool as to act on the leather 90 during the continuance of the softened condition given by the tool, and being constructed to mold the softened edge into finished form.

48. A machine for finishing the edge of a piece of leather comprising a support for said piece, a searing tool arranged to act on the margin on one side of said piece, a molding member arranged to act upon the edge of said piece subsequently to the action of the searing tool, a turntable and a feed roll which coöperate to feed said piece, and means for rotating said turntable and roll.

44. A machine for finishing the edge of a piece of leather comprising a support for said piece, a searing tool arranged to act on the margin on one side of said piece, an edge gage shaped to bend the edge of said piece toward said tool, a molding member arranged to act upon the edge of said piece 100 subsequently to the action of the searing tool, a turntable and a feed roll which coöperate to feed said piece, and means for rotating said turntable and roll.

45. A machine for finishing the edge of a piece of leather comprising a support for the piece, a searing tool in the form of a highly heated electric conductor, and means for applying said tool to the margin of said piece on the flesh side whereby said margin is 115 shrunk and the grain side curled toward the flesh side to present a finished edge.

46. A leather edge-finishing machine comprising a work support, a post rising above said work support, a searing tool held by 125 said post at a distance above the work support approximately equal to the thickness of a thin sheet of leather, an edge guide rising from the work support adjacent to the searing tool, and a rotating feed roller above 130

- the work support and near said edge guide, arranged to rotate in a plane making an oblique angle with a line from the searing tool to the active point of the roll. 55
- 5 47. A machine of the character described comprising a rotating member or turntable having a face adapted to support the edge of a leather piece, a feed roll arranged over said turntable for engaging a piece laid on 60
- 10 said turntable, a molding member arranged to be engaged by the edge of a piece held by said turntable and feed roll, and having a flange overhanging the adjacent part of the table, and a heated searing tool adjacent to said turntable, a stud arranged to be engaged by said feed roll in position to heat the surface, adjacent to the edge, of a piece engaged by said roll. 65
- 15 48. A machine of the character described comprising a rotating member or turntable having a face adapted to support the edge of a leather piece, a feed roll arranged over said turntable for engaging a piece laid on 70
- 20 said turntable, a stud arranged to be engaged by the edge of a piece held by said turntable, and having a flange overhanging the adjacent part of the table, and a heated searing tool adjacent to said feed roll in position to heat the surface, adjacent to the edge, of a piece engaged by said tool, and means for supporting said tool. 75
- 25 49. A machine for finishing the edge of a piece of leather comprising a support for the piece, a searing tool, means for producing relative movement between said piece and tool to sear the margin of the piece, and means whereby said tool may be adjusted vertically. 80
- 30 50. A machine for finishing the edge of a piece of leather comprising a support for the piece, a searing tool, means for producing relative movement between said piece and tool to sear the margin of the piece, and means whereby said tool may be adjusted angularly. 85
- 35 51. A machine for finishing the edge of a piece of leather comprising a support for the piece, a searing tool, means for producing relative movement between said piece and tool to sear the margin of the piece, and means whereby said tool may be adjusted horizontally. 90
- 40 52. A machine for finishing the edge of a piece of leather comprising a support for the piece, a searing tool, resilient means for permitting said tool to yield in a direction substantially perpendicular to the surface of said piece, and means for causing relative movement at a substantially uniform rate of speed between said tool and piece to sear the margin of said piece. 95
- 45 53. A leather edge finishing machine comprising heat applying means adapted to be maintained at a temperature higher than that at which decomposition of leather commences, and means for producing relative movement between a leather piece and said heat applying means at a substantially uniform speed in one direction in a path such that said heat applying means is caused to act upon a narrow area of one surface of the piece at the margin thereof, whereby such surface is shrunken and the opposite edge of the margin is curled toward such shrunken surface. 100
- 50 54. A leather edge finishing machine comprising an operating tool, means for propelling and guiding a piece of leather past said tool in a path such that the tool makes contact with one surface of the piece at the margin thereof, and means for heating the tool to a temperature at which it will cause shrinkage of the leather with which it makes contact, said tool-heating means being constructed and adapted to limit the application of heat to the tool itself. 105
- 55 55. A leather edge finishing machine comprising in combination heat applying means, complemental gripping and feeding means constructed and arranged to propel a leather piece past such heat applying means in a path wherein the marginal portion of one surface of the piece is subjected to the action of the heat applying means, and a pressure exerting member against which the edge of the piece is compressed progressively by said gripping and feeding means as it leaves the heat applying means. 110
- In testimony whereof we have affixed our signatures, in presence of two witnesses.
- EDWARD S. HALSEY.
GEORGE G. PERKINS.
- Witnesses:
- THOMAS F. PORTER,
GEORGE BIRDSEYE.
